UNITED STATES PATENT OFFICE

BENJAMIN H. FREEDMAN, OF NEW YORK, N. Y., ASSIGNOR TO HUDSON HOLDING CORPORATION, OF NEW YORK, N. Y., A CORPORATION OF DELAWARE

MATCH PACKAGE

Application filed April 30, 1930. Serial No. 448,452.

This invention relates to a match package of the "book type," such as is shown in my co-pending application for patent, Serial No. 442,753 filed April 9, 1930.

5 The object of this invention is to provide an improvement in the type of package shown therein and to produce a package in which the possibility of the matches contained therein being accidentally ignited is entirely avoided. My invention relates particularly to a means for covering and consequently protecting the heads of the matches in the package so that it is not possible for the same to be brought in frictional contact with some object or objects that might be contained in the user's pocket, whereby the matches would be accidentally ignited.

10 The primary object of my invention therefore, is to provide a package in which the features of safety are greatly stressed to such an extent that it is practically impossible for accidents to be caused through the use of a match package such as is made in accordance with this invention.

15 With these objects and such other objects as may hereinafter appear, in view, I have devised the particular arrangement of parts set forth below and more particularly pointed out in the claims appended hereto.

20 Reference is to be had to the accompanying drawings, forming a part hereof in which

Figure 1 is a front elevation of a match package made in accordance with my invention and in an open position;

25 Figure 2 is a plan view of the same;

Figure 3 is a transverse view of the closed package;

Figure 4 is perspective view of the closed package; and

30 Figure 5 is a perspective view of a modification.

Throughout the various views of the drawings, similar reference characters designate similar parts.

35 In the embodiment of my invention disclosed in the accompanying drawings, 1 indicates the elongated strip of paper from which the package covering is formed. This cover strip has one of its ends inturned to form a short flap 2 and this flap 2 acts as a

binding means for holding the match strip 3 within the package. The match strip 3 is held under the inturned flap 2 by means of a wing 4 provided along one edge of the match strip, which wing extends parallel to the axis of the strip 3 and projects from one of the sides thereof and lies beneath the inturned flap 2.

40 At 5 is shown a fastening staple which extends through the flap 2, through the wing 4 on the match strip 3 and through the body portion 1 of the paper cover strip, thus securely holding the match strip 3 in position. It will be seen that the match strip 3, in the construction provided, extends transversely of the entire paper covering strip 1 and the match strip 3 is further secured to the paper cover strip 1 by means of another staple 6 which extends through the match strip and through the cover 1.

45 The staple 6 is located at right angles to the staple 5 and it passes through the narrow marginal portion 7 located along the bases of the matches in the strip 3. The staple 6 is preferably located adjacent to the fold 8 in the cover strip 1 so that when the flap portion 9 of the cover 1 is folded, it is prevented by the staple 6 from entering behind the match strip and exposing the match heads to possible frictional contact with some object or objects that the match user may carry in his pocket.

50 The cover flap 9 is provided with an abrasive strip 10 which is preferably located along one of its side edges, such edge being that which is remote from the match heads in the strip.

55 In the type of package forming the subject of my invention, it will be seen that the match heads are located toward what would be an open side of the package, so that unless said match heads were covered in some way, the same would be likely to contact with objects in the user's pockets. To wholly cover the match heads when the package is closed, I provide a wall 11. Said wall 11 consists of a flap formed on the edge 12 of the cover strip 1. Said flap is inwardly folded as at 13 and thence outwardly folded as at 100

14, to provide a fairly rigid projecting portion 15.

As will be seen in Figures 1, 3 and 4, a marginal part 16 is provided between the two folds 13 and 14 and a staple 17 extends through the two thicknesses of material thus provided and acts to supply rigidity to the structure and maintain the wall 15 in a substantially rigid condition.

10 As the heads of the matches in the strip 3 are located adjacent to this wall 15 or even in actual physical contact therewith, said wall 15 is maintained in its substantially rigid form and acts to wholly close the end 15 of the package whereat the match heads are located.

The edge 18 of the wall 15 is suitably curved or shaped so as to conform to the curvature of the cover flap 9, as shown in dotted lines in Figure 2, when said flap is closed.

15 In Figure 5, I have shown a modification of my invention wherein a match book of the conventional type is shown. This book is provided with the usual cover strip 20, innered flap 21 and match strip 22. In a match book of the character disclosed in Figure 5, the matches in the strip 22 are exposed at the sides of the package. I avoid such exposure of the matches by providing 20 the longitudinal sides 23 and 24 of the package with lateral wings or extensions 25 and 26 which are folded inwardly and upwardly as disclosed to provide upright protective walls and, when the package is closed, to close 25 what was formerly the open sides of the package. A staple 27 passing through the inwardly bent base portion of the wings 25 and through the body of the covering strip securely maintain these walls in their up- 30 right position.

35 From the foregoing, it will be seen that I have provided a match package in which the features of safety are greatly stressed. The heads of the matches are, when the package 40 is in its closed condition and carried in the package, wholly covered by the protecting wall located adjacent to them. Thus, it is impossible for the matches to be accidentally ignited in the pocket, since the heads 45 thereof cannot be brought into contact with any object carried by the match user.

50 Additionally, by reason of the position of the striking strip, it is necessary to close the cover flap before a match can be struck.

55 Having described several embodiments of my invention, it is obvious that the same is not to be restricted thereto but is broad enough to cover all structures coming within the scope of the annexed claims.

60 What I claim is:—

1. A match package having a cover strip, a match strip extending crosswise on said cover strip and adapted to have portions of said cover strip folded over it, and a wall provided 65 along one edge of said cover strip, said wall

consisting of an infolded wing on the cover strip having its base fastened to the cover strip and its body portion projecting outwardly from its point of securement.

2. A match package consisting of a cover strip and a match strip held therein, a wing provided on one edge of the cover strip, said wing being inwardly and thence outwardly folded on the cover strip to provide an outstanding protective wall for the match heads, and a fastening member passing through said wing between its folds.

3. A match package consisting of a cover strip and a match strip held thereon, a wing provided on one edge of the cover strip, said wing being inwardly and thence outwardly folded on the cover strip to provide an outstanding protective wall for the match heads in the match strip, the area of said wing that is located between the folds being fastened to the body of the cover strip.

Signed at the city, county and State of New York, this 29th day of April, 1930.

BENJAMIN H. FREEDMAN.
